(57) CLAIM

The ornamental design for a pillowcase having pockets for receiving hands and feet, as shown and described.

DESCRIPTION

FIG. 1 is a top and bottom left end perspective view showing one embodiment of my new design.

FIG. 2 is a top plan view thereof.

FIG. 3 is a bottom plan view thereof.

FIG. 4 is a top and bottom right end perspective view thereof.

FIG. 5 is a left end view thereof.

FIG. 6 is a right end view thereof.

FIG. 7 is a side view of the embodiment of FIG. 1 with the pillowcase containing a pillow and showing a user in broken lines.

FIG. 8 is a top and bottom left end perspective view showing a second embodiment of my new design.

FIG. 9 is a top plan view thereof.

FIG. 10 is a bottom plan view thereof.

FIG. 11 is a top and bottom right end perspective view thereof.

FIG. 12 is a left end view thereof.

FIG. 13 is a right end view thereof; and,

FIG. 14 is a side view of the embodiment of FIG. 8 with the pillowcase containing a pillow and showing a user in broken lines.

In the drawings, the broken lines showing a user in FIGS. 7 and 14 form no part of the claimed design.
